UNITED STATES PATENT OFFICE.

WILLIAM C. BRYAN, OF NASHVILLE, TENNESSEE.

DUMPING-WAGON.

SPECIFICATION forming part of Letters Patent No. 296,670, dated April 8, 1884.

Application filed November 15, 1883. (No model.)

To all whom it may concern:

Be it known that I, WILLIAM C. BRYAN, of Nashville, in the county of Davidson and State of Tennessee, have invented certain new and 5 useful Improvements in Dumping-Wagons; and I do hereby declare the following to be a full, clear, and exact description of the same, reference being had to the accompanying drawings, forming part of this specification, and to 10 the figures and letters of reference marked thereon.

My invention relates particularly to that class of wagons used for transporting bricks, coal, and similar material, though of course it 15 is generally applicable to wagons used for other purposes. Its novelty consists in a certain improved construction and combinations of parts, hereinafter to be described and claimed, whereby the wagon is rendered self-dumping.

20 My invention will best be understood when described in connection with the accompanying drawings illustrating it, wherein—

Figure 1 represents a top plan view of my improved wagon; Fig. 2, a side elevation of 25 the same; Fig. 3, a longitudinal vertical section taken on the line xx of Fig. 1.

Similar letters of reference in the several figures denote the same parts.

The letter A represents the rear axle of the 30 wagon, and the letter B the front axle of the same, both axles being provided with ordinary transporting-wheels, as shown. The front axle has mounted upon it and connected to it through an ordinary fifth-wheel a bolster, C, 35 and supported upon this bolster and upon the rear axle is an inclined frame, D, composed of side bars and a front bar or cross-piece, as shown.

E represents the body of the wagon, supported upon the side bars of the frame D by a cross-bar, F, at the rear, rollers G at the middle, or thereabout, and smaller rollers h at the front end. The side bars of the frame are protected upon their upper bearing-surfaces 40 by metal protecting plates or tracks I, extending from a point forward of the bearing-points of the front rollers, h , back of the rear axle, where they are curved up and formed into guards or stops J. The portions of the side 45 bars of the frame which extend past the stops or guards J, and upon which the cross-bar F of the body rests, are also protected or shod

with metal plates K. Secured to the body at or near the point of attachment of the rollers H are downwardly-projecting arms L, which 55 serve to hold the forward end of the body in place and prevent it from moving laterally. The rollers or wheels h are preferably provided with flanges, so as to prevent lateral displacement of the body at the middle, and also 60 for the purpose of guiding and properly directing the body when moving down the inclined plane, the downwardly-projecting arms also assisting in the accomplishment of this end.

To the forward portion of the body, at opposite sides thereof, are pivoted, so as to swing up and down freely, hooked arms M M. When the body is moved up the inclined frame from the rear, these arms M hang down, with their forward shouldered ends below or on a line 70 with the bottom of the body, and as the body advances up the incline they strike inclined guides N N, secured to the bolster, and are raised by said guides and caused to pass up over and engage with a cross bar or rod, O, 75 extending from side to side of the frame D.

Mounted upon a rock-shaft, P, extending from side to side of the front end of the frame D, are two U-shaped arms, Q Q. The general form of these arms is U-shaped, though the 80 upper part or branch is slightly longer than the lower part or branch. Normally these U-shaped arms stand opposite the inclined guides N N, with their upper branches above the cross-rod E and their lower branches below 85 said cross-rod, as shown in Fig. 3, they being held in this position by the tension of a coiled spring, R, secured to the rock-shaft P, and having its free end bearing against cross-rod O. As the shouldered ends of the hooked 90 arms M pass up the guides N N, the points of the said arms strike the upper part of the U-shaped arms Q Q and raise the same, and hold them raised until the shouldered ends of the hooked arms drop into engagement with the 95 cross-rod O, when the U-shaped arms are again depressed by the operation of the spring R, and serve to hold the said hooked arms M in engagement.

If it is desired to dump the load, the rock-shaft P is rocked by means of a hand-lever, S, applied to one of its ends, and the U-shaped arms Q Q are caused to swing up, and in so doing positively lift the ends of the hooked

arms M M and free them from the rod O. The body, being thus released, moves down the incline frame upon the rollers G and h until the cross-bar F of the body at the rear passes off 5 of the side bars, whereupon the body tilts down upon the axles of the wheels or rollers G as a center and strikes two other rollers, T T, located on the frame over the rear axle, as shown in Fig. 3. The body, in its tilted 10 condition, continues down the inclined frame until its rollers G come in contact with the stops or guards J. After the load has slid out of the body, the latter is tilted up until its forward rollers, H, again rest upon the incline frame, and it is then moved up the frame 15 until its hooked arms again engage with the cross-rod P, as before. It will be observed that as soon as the hooked arms are disengaged from the rod P by the tilting of the rock- 20 shaft the dumping of the load is effected automatically.

Where an automatically-opening end-gate is not employed, it will be necessary to let down the end-gate before operating the lever 25 S to disengage the hooked arms.

Having thus described my invention, I claim as new—

1. In a dumping-wagon, the combination, with the inclined frame, of the body provided

with the rollers at or near its middle, and also 30 near its forward end, and the cross-bar at its rear end, and the stops or guards upon the inclined frame, whereby the middle rollers, coming in contact with the said stops or guards, permit the body to be tilted upon the axles of 35 said rollers, substantially as described.

2. The combination of the inclined frame with the body, the pivoted hooked arms pivoted to the body, the incline for automatically raising the hooked arms, and the rod with which the 40 hooked arms engage, substantially as described.

3. The combination, with the inclined frame, of the body, the pivoted hooked arms, the rod 45 with which they engage, and the U-shaped arms mounted on the rock-shaft, substantially as described.

4. The combination, with the inclined frame, of the body, the pivoted hooked arms, the inclined guides for raising said arms, the rod 50 with which the arms engage, the rock-shaft and its U-shaped arms, and the spring upon the rock-shaft, substantially as described.

WILLIAM C. BRYAN.
